G. L. DULANEY AND J. A. KAUFMAN, OF MECHANICSBURG, PENNSYLVANIA.

Letters Patent No. 75,741, dated March 24, 1868.

IMPROVEMENT IN RAILROAD-SWITCHES.

The Schedule referred to in these Letters Patent and making part of the same.

TO ALL WHOM IT MAY CONCERN:

Be it known that we, G. L. DULANEY and J. A. KAUFMAN, of Mechanicsburg, Cumberland county, Pennsylvania, have invented new and useful Improvements in Railroad-Switches; and we do hereby declare that the following is a full and exact description thereof, reference being had to the accompanying drawings, making part of these specifications.

Figure 1 represents a top or bird's-eye view of the several parts embraced in our improvements in railroad-switches.

Figure 2 is an elevated side view of said improvements, showing the position of the self-adjusting gravitating-weights, with truck in position on the main track.

Figure 3 is an end view of a truck on the main track, showing the position of the adjusting-rod E at the moment of being brought into action with the inclined lever B³, in order that the track may be shifted to the right-hand sideling, (see dotted lines fig. 1.)

The construction and operation of our improved railroad-switch consists in providing the adjustable rails *a a* of the main track with a self-adjusting gravitating-weight, (see *a²*, fig. 2.) Said weight is suspended on a fulcrum, D, at any proper point beneath, and midway between the ends of the two movable rails of the main track by a connecting-rod, *c*, said rod connecting, at its upper end, with the bar L, that connects with and carries the switch from one position to another when desired. The rod *c* is furnished with a joint between its fulcrum and weight, in order to arrest the shock consequent upon a sudden movement of the switch. The office of said weight, *a²*, is to hold securely, (when in a vertical position and at rest,) the switch in line with the main track at all times, unless it is desirable to run in the sideling. When this is the case, the resistance of said weight is overcome by the action of the train and levers, as hereinafter mentioned.

Our improvement consists in further providing a switch with suitably-arranged and inclined levers B² B³, with properly-arranged connecting-rods *o o*, &c., in order that the switch may be adjusted by the train or car, while in motion, without the assistance of an extra "switch-tender." The levers B² B³ are securely bolted to the cross-tie, at the proper point near the front end of the switch; said levers being connected near their middle to each end of the cross-bar L. B³ B² are elbow-shaped levers, situated and securely bolted at a point as remote from the front end of the switch as the largest car. *o o* are rods, connecting the elbow-levers B³ B² with the cross-bar T that moves the bar L, carrying with it the rails *a a* when being adjusted from one position to another, (see fig. 1.)

In order to provide for greater security, we furnish our improved switch with a self-adjusting, gravitating, bolting-device, (see figs. 1 and 2.) In the construction of this peculiarly-arranged device, we furnish the bolts D¹ D¹ with gravitating-weights *a³*. Said weights are suspended to rods attached to the switch-rails, and projecting downwards a sufficient distance to form the fulcrum for the rod on which the weights are suspended. These weights are also provided with joints, to arrest any sudden action of the train thereon, (see D², fig. 2.) The upper ends of the rods on which the weights are suspended are provided with an inclined slot. Said slot bearing against pins projecting from the sides of the bolts, (see fig. 2,) keeps the bolts up a sufficient distance to allow the switch being adjusted when desired.

The bolts, as above described, are connected to the switch-rails by short inclined links or bars at such an angle as will insure their depression as soon as the wheels of the train come in contact with the bolts D¹ D¹, fig. 2, thus bringing the bolts down on each side of the stationary rails in front, and substantially holding the switch in position during the passage of the train over the same. Immediately after the passage of the train the bolts are disengaged, leaving the switch free for adjustment, if desired; the weights bringing them to their proper position, as the bolts are intended only to be engaged when the train or car is passing over the switch.

In order to facilitate the labor consequent upon frequent switching on and off the sideling, we provide each corner of a locomotive or car with suitably-arranged rods, said rods projecting downwards from the platform of each car to a point near the adjusting-levers B³ B², fig. 3 and fig. 2, and just above the track. These rods E E are provided at their upper ends with any desirable form of spring, to keep said bolts up and disengaged when running on main track. Their lower ends are secured in a proper position by suitably-arranged and substantial braces provided therefor.

When it is found necessary to switch on or off the sideling, all that is necessary on the part of the driver or brakeman, is to press down the rod E with the foot, (see fig. 3,) until it comes in contact with the lever B³, and as the car moves forward, said rod pressing against the inclined lever, causes the switch to move over to the sideling, (see dotted lines, fig. 1.) The same process is observed in backing out of a sideling. Press the rod down, when it will come in contact with the lever B², at the front end of the switch, and cause it to bring the switch to the proper position to run the train out on the main track.

Having fully set forth and described the nature and construction of our improved railroad-switch, what we claim, and desire to secure by Letters Patent of the United States, is—

1. The gravitating-weight α^2 , with its jointed connecting-rod and fulcrum, in combination with the switch-rails α α , in the manner and for the purpose herein described.

2. The combination of the inclined levers B² B³, with the rods σ σ , in the manner and for the purpose herein described.

3. The combination and arrangement of the weights α^3 , bolts D¹ and switch rails α α , in the manner and for the purpose herein described.

G. L. DULANEY,
J. A. KAUFMAN.
